SUPPORT FOR A TOROIDAL COIL
 Kenneth P. Gorman, % Gorman Machine Co.,
 480 S. Main St., Randolph, Mass.
 Filed Apr. 29, 1957, Ser. No. 655,574
 3 Claims. (Cl. 242—4)

The present invention relates to a device for supporting toroidal coils particularly during the process of manufacturing these coils.

In the art of toroidal coil winding it is common to wind the doughnut-shaped cores which form the base of the coils by passing a split-ring through the core. Wire is then wound onto the split-ring and subsequently is transferred to the core by dropping the wire from the split-ring onto the core as the split-ring is rotated. In the devices which are commonly used for manufacturing coils in this fashion, it has been a common expedient in the art to secure the core during the formation of the coil by a clamping element. The clamp and core are rotated by the operator during the winding process in order to obtain an even winding of the core. The operator must loosen the clamp and tighten it once again about the core over already wound sections, at least once during each operation, in order to completely wind a toroid. Very often the core must be removed from the clamp several times during the processing of a single coil for the purpose of permitting individual segments to be wound. In addition to difficulties in clamping and unclamping and in addition to the substantial time consumption performing such clamping and unclamping operations the prior art structures utilized for supporting cores were not satisfactory in properly centering a core for this winding procedure.

The present invention is designed to overcome these defects of prior art structures and has other unenumerated advantages which will be more clearly understood when considered in connection with the accompanying drawings in which:

FIGURE 1 is a side elevation of the present invention,
 FIGURE 2 is a front elevation of the present invention,

FIGURE 3 is a top plan view of the present invention.

FIGURE 4 is a cross-sectional view taken along the line 4—4 of FIGURE 1,

FIGURE 5 is a cross-sectional fragmentary view of a modification of the invention, and

FIGURE 6 is a cross-sectional view taken along the line 6—6 of FIGURE 5.

This particular support illustrated and claimed in the present case is designed to be used in connection with small toroidal coil winders. In machines of this general type there is provided a drive mechanism and a removable split ring driven thereby. This split ring which ordinarily has a diameter of approximately 3" is formed with a channel along its outer periphery adapted to receive a quantity of wire. The ring is mounted on the drive mechanism and passed through the core to be wound into a toroid coil. The core is mounted on the split ring by merely opening the ring and passing it through the core and then reclosing it. After the core is so mounted the ring is rotated in a reverse direction during which time a quantity of wire is wound upon the ring. After a desired amount of wire is wound on the ring the end of the wire is secured or passed about the core forming one terminal of the toroidal coil. The split ring is then rotated in a forward direction and the wire is slipped from the ring, upon each rotation of the ring, and transferred to the core. Simultaneously, the core is slowly rotated to obtain a distribution of the windings about the core.

The supporting member, illustrated in the accompanying drawings, is rotatedly fixed to the winding machines for support of the core. In this structure there is provided a cylindrical base 1 having an axial bore 2 extending there-

2

through. The outer surface of the cylindrical section may be knurled for ease in handling. The diameter of the bore 2 should be sufficient to fit over a locating pin on the winding machine. This locating pin, in turn, should be so positioned as to permit the support of a core for operative engagement with the rotatable split ring. Extending upwardly from the upper surface 3 of the cylindrical surface is a supporting column generally indicated at 4. This supporting column is formed with one longitudinal surface comprising a quadrant arc continuous with a segment forming a wall of the bore 2. Walls 6 and 7 normal to each other are continuous with the wall 5. The outer ends of the walls 6 and 7 are continuous with the wall 8 which is a quadrant sector of a frustum. At the upper end of this supporting member is a semi-cylindrical supporting head 9. This head is substantially a 180 degree arc concentric with the bore 2 and with its diametrical edge substantially aligned with one of the walls 6 or 7. The upper surface of this semi-cylindrical member provides a top surface 10 for supporting a core 11. Projecting upwardly from the opposite extremities of the supporting head are a pair of pins 12 and 13 which are designed to engage a core 11 and secure it in position, preventing it from being pulled forward towards the winding machine. The pins 12 and 13 are preferably flat and thin in cross section.

The core 11 is placed upon the surface 10 by the operator and the split ring 14 is opened and passed through the core with the ring projecting through the arcuate recess 15. In this arrangement the ring 14 may be rotated in either a clockwise or counterclockwise direction and the core 11 may also be rotated in either a clockwise or counterclockwise direction about the ring section which passes through it. For winding of the side of the core 11, opposite the pins 12 and 13, the core 11 may be lifted slightly to clear the wire which passes from the ring to the core and then rotated until the desired section is located between the two pins. The entire support may be slowly rotated as desired, by the operator, by grasping the support at its base 1.

A modification of this invention is illustrated in FIGURES 5 and 6. In this modification there is provided a base support 30, similar to supporting base 1. This base 30 is provided, however, with an oversize bore 31. Within this oversize bore 31 there is positioned a cylindrical "oil-lite" bearing 32 which comprises a sleeve of bearing oil-impregnated metal. This bearing has an outer diameter of approximately, for example, of $\frac{3}{8}$ " while the inner diameter of the bore may be, for example, $2\frac{7}{64}$ ". The bearing is preferably coextensive with the bore and is adjustably supported within the bore by a plurality of set screws 33. These set screws 33 may be arranged in two groups, an upper group and a lower group. Each group may comprise four set screws arranged radially and 90 degrees from one another. By proper adjustment of the set screws the bearing may be moved farther or closer to one wall of the supporting base. In this manner small adjustments of the inner bearing may permit an adjustable alignment of different cores with the split ring. This type of arrangement avoids the necessity of providing a plurality of different sized supporting members for different types of cores.

Having now described my invention I claim:

1. A support for a core adapted to be used in a toroidal core winding device comprising an arcuate surface having an inner arcuate edge extending nearly 180°, a pair of parallel pins extending normally from said surface at opposite ends thereof, a cylindrical base having a longitudinal opening therethrough with the axis of said opening passing through the center of curvature of said arcuate inner edge, and a supporting arm integral at opposite ends with said surface and the upper surface of said cylindrical

base and having at least part of one wall thereof parallel with lines passing through and normal to said arcuate surface.

2. A support for a core adapted to be used in a toroidal core winding device comprising an arcuate surface of nearly 180° adapted to support the bottom of said core, a pair of pins extending normally from said surface at opposite ends thereof and against which said core is adapted to bear, a base having an opening with an axis passing through the center of curvature of said arcuate surface, said pins having flattened surfaces radial with respect to said axis and against which a toroidal core is adapted to bear, and a supporting arm interconnecting said base and surface.

3. For use with a split annular ring adapted to wind a toroidal core, a toroidal core support having an arcuate

supporting surface extending nearly 180° about a line normal to a plane passing through said surface, said surface adapted to slidably support the bottom of a toroidal core, a pair of parallel pins extending normally from said surface only at opposite ends thereof and adapted to engage the wall of the bore of said core, a base having a longitudinal opening with an axis coincident with said line, and a supporting arm interconnecting said base and surface.
